UNITED STATES PATENT OFFICE.

OTTO HEER, OF ZURICH, SWITZERLAND.

ROLLING-MILL FOR THE MANUFACTURE OF PIPES AND OTHER HOLLOW BODIES.

No. 894,140.

Specification of Letters Patent.

Patented July 21, 1908.

Application filed September 28, 1905. Serial No. 280,533.

To all whom it may concern:

Be it known that I, OTTO HEER, a citizen of the Swiss Confederation, and resident of Zurich, Switzerland, have invented new and useful Improvements in Rolling-Mills for the Manufacture of Pipes and other Hollow Bodies, of which the following is a specification.

This invention has for its object a device for rolling-mills for manufacturing pipes and other hollow bodies, intended to give to the work-pieces on the core-bar, which are to be stretched, piece by piece, by means of two grooved rollers journaled in a stationary frame, the motion required for this kind of rolling, that is to say a to and fro motion, in which the advance is greater than the retrogression. From the constructions now in use for producing this kind of motion the present invention differs, in the main, in that respect that at the end of the advance motion, in addition to the avoidance of shocks, the temporary fixing of the work-piece is effected, in order to prevent the troublesome recoil of the piece, which occurs at the moment of its striking against the rigid or resilient organs serving to limit its course, if the to and fro motion is very rapid. By means of this device it is also possible to adjust the work-piece at the beginning of the rolling process without touching it with the hands and independently of the driving power of the rolling-mill, and to bring it rapidly into the right position for the grooved rollers, and to bring, on the termination of the rolling, the core-bar back in the same manner into the position required for removing the rolled pipe and for putting on a new work-piece.

On the accompanying drawings such a device is illustrated on Sheet I and in Figure 1 in a side-view and partly in a longitudinal section, and in Fig. 2 in a longitudinal section, on Sheet II in Fig. 3 in a horizontal section on the line $x-x$, and in Fig. 4 in a cross-section on the line $y-y$.

Similar letters refer to similar parts throughout the several views.

The core-bar b which carries the work-piece a on its front half, and secures it against retrogression, is provided on its hind part with a thread and a longitudinal groove and screwed into a nut e rigidly journaled in the middle of a cross piece f ; the ends of this cross-piece, which form eyes or hooks, are fixed on two bars g , each of which is carried

by two blocks i and k , sliding lengthwise between guide-rails n , n' , and of which the front-blocks i are rigidly united with the corresponding bars g , while the hind-blocks can be shifted along the same. Both blocks, on each side, are united by means of a resilient strut consisting of two pairs of links l and l' and a spiral spring m arranged between the vertexes of the same. With the pins of the two hind-blocks k , which serve to carry these struts, engage the pushing-bars w^1 of a crank shaft w , which can be rotated by the working-shaft of the working roller by means of an intermediate shaft v provided with a detachable coupling u^1 .

Before each of the front blocks i and connected with the same by a bar g^1 is arranged a wedge-shaped block h guided by the lower rail n of the slide. The end of this slide which rests on the roller-frame o forms a shoe, that is to say a casing open in front and at the back. In this casing is provided a cover-plate, which can be shifted in an upward direction at a right angle with the slide and within certain limits, which plate is constantly held by two spiral springs r , arranged below the cover of the shoe, in its lowest position.

In front of the nut e , and on the same axis, a toothed wheel c , which can be rotated but not be shifted, has been arranged on the cross-piece f whose central bore encompasses the rod b of the core-bar and receives a wedge which engages the longitudinal groove on the threaded part of this bar. This toothed wheel c constantly engages with a long toothed drum s arranged between the two slides of the blocks i , k , and which is turned by a special motor t , but can, when this motor has been uncoupled, be moved by successive starts by the intermediate shaft u running parallel with it, by means of a detent v provided with a pawl v^1 and actuated by an eccentric u^2 and its rod.

This device works as follows: The core-bar b , after receiving the work-piece a , is rotated by the motor t , and thereby screwed out of the nut e and advanced until the front-end of the work-piece has passed through grooves in the caliber of the working-rollers and is thus between the same. When after the uncoupling of the motor these rollers are then rotated the work-piece, which is then stretched by these rollers, is, under their action, pushed back a certain distance until it is forced, after its temporary release, which

takes place at the moment the caliber grooves close together over the rolled part, by the cross-piece *f*, advanced at this moment by the crank shaft *w*, to participate in 5 the forward movement of the same. During this advance a temporary rotation of the drum *s* and of the wheel *c* is produced in consequence of the forward swinging of the pawl *v*¹ caused at the same time by the eccentric 10 disk *u*², and thereby is effected, in addition to a rotation of the bar *b*, to the extent of 90°, the forward screwing of the same a distance equal to the difference between the advances and the retrogressions of the work-piece.

15 Shortly after the termination of the advance of the work-piece the wedge-shaped blocks *h*, which were forced to participate in this movement, enter into the shoes at the end of their slide, whose cover-plates *q* they 20 press upwards, against the action of the spiral springs *r*, until these plates touch the upper surface of the space in which they move. Hereby the plates, and at the same time the blocks *h*, are secured and held in this temporary 25 position, and through the rod *w*¹ still advances, the cross-piece *f* and the core-bar *b* with the work-piece *a* stand still until the calibers of the working-rollers, which at this moment close together cause the retrogression 30 of the said parts and thereby also of the blocks *h* and their release from the shoes. This retrogression is effected, without the co-operation of the crank shaft *w*, solely by the action of the rotating working-rollers upon 35 the work-piece, while the still greater advance-movement of this piece is only caused by the shaft acting on the cross-piece *f* and by the forward-screwing of the core-bar *b*, which takes place at the same time.

40 In order to prevent a disturbing action of the crank shaft on the cross-piece *f*, and the parts rigidly united with it, during the retrogression of the same, caused by the working-rollers, struts have been provided between 45 the blocks *i* and *k* which moreover have the object to allow of the further advance of the cranks of the shaft, until they reach their dead point, after the wedge-shaped blocks *h* have already been secured before this happens. By the bending of their links *l* *l*¹ these struts allow of the variations in the distance 50 of the two blocks *i* and *k* from each other, which occur during the two working-phases, while under the action of their springs *m* the 55 distance between the blocks, after each

change, is always reduced again to the normal bounds.

What I claim as my invention and desire to secure by United States Letters Patent is—

1. In a tube rolling mill the combination of a stationary frame, a pair of rollers at one end thereof, a core bar, a pair of movable rods carrying the bar, a pair of blocks connected with each rod, one block of each pair having yielding movement in relation to its rod while the other block of the pair is firmly connected to its rod, resilient means connecting the blocks of each pair and actuating means connected to the movable blocks. 70

2. In a tube rolling mill the combination of a stationary frame, a pair of rollers at one end thereof, a core bar, a sliding block having rigid connection with said bar, a second sliding block connected with said bar but having movement relative thereto, a resilient strut connecting the two blocks and actuating means connected to the movable block. 75

3. In rolling mills for drawing out pipes, two rollers and means for advancing the work piece between the rollers and means for braking and securing the work piece during its advance, said means consisting of two wedge shaped pieces *h* carried by the advancing means, the fixed casing *p* for receiving said pieces, a cover plate for the casing movable upwardly and the spiral springs pressing down the cover plate against the wedging action of the wedge shaped pieces. 80

4. In rolling mills for drawing out pipes, a frame, two rollers, a core bar for carrying the work piece between the rollers, a cross piece carrying said core bar, a pair of rods supporting the cross piece, a sliding block supported and guided on the frame and supporting each end of each rod, the blocks at one end of the rods having sliding movement thereon, a resilient strut connecting the blocks of each pair together, said strut consisting of two pairs of angle links and a spiral spring located between the inner ends thereof and means for reciprocating the rearmost blocks. 90

In testimony whereof I have signed my name to this specification in the presence of two subscribing witnesses.

OTTO HEER.
